CLAIM

The ornamental design for a canopy for aircraft bridge or similar article, substantially as shown and described.

DESCRIPTION

FIG. 1 is a side elevational view of a canopy for aircraft bridge, or similar article, showing one side of my new design, the opposite side thereof being identical thereto; FIG. 2 is a perspective view thereof; FIG. 3 is a side elevational view, showing the canopy in another position, the opposite side of the view being identical thereto.

FIG.1

FIG. 2

FIG. 3
